US00D792410S

(12) **United States Design Patent** (10) **Patent No.:** **US D792,410 S**
(45) **Date of Patent:** **** Jul. 18, 2017**

(54) **SMART CARD INTERFACE**

(71) Applicant: **NagraStar LLC**, Englewood, CO (US)

(72) Inventors: **William Michael Beals**, Englewood, CO (US); **Hervé Goupil**, Villars sous Yens (CH)

(73) Assignee: **Nagrastar LLC**, Englewood, CO (US)

(***) Term: **15 Years**

(21) Appl. No.: **29/567,135**

(22) Filed: **Jun. 6, 2016**

Related U.S. Application Data

(62) Division of application No. 29/448,754, filed on Mar. 13, 2013, now Pat. No. Des. 759,022.

CLAIM

The ornamental design for a smart card interface, as shown and described.

DESCRIPTION

FIG. 1 is a perspective view of a smart card interface; FIG. 2 is a top view thereof; FIG. 3 is an enlarged top view thereof; FIG. 4 is a perspective view of the smart card interface in accordance with a second embodiment; FIG. 5 is a top view thereof; and, FIG. 6 is an enlarged top view thereof. The illustrative broken line showing of a base surface throughout the drawing figures depicts an exemplary component to which the smart card interface might be applied and forms no part of the claimed design.
